(57) **CLAIM**

The ornamental design for an engine accessory mounting bracket, as shown and described.

DESCRIPTION

FIG. 1 is a front view of the engine accessory mounting bracket;

FIG. 2 is a top view of the engine accessory mounting bracket;

FIG. 3 is a bottom view of the engine accessory mounting bracket;

FIG. 4 is a perspective front view of the engine accessory mounting bracket;

FIG. 5 is a side view of the engine accessory mounting bracket;

FIG. 6 is an opposite side view of the engine accessory mounting bracket;

FIG. 7 is a back view of the engine accessory mounting bracket; and,

FIG. 8 shows the engine accessory mounting bracket in an environmental use.

The broken lines in FIGS. 1, 4, 7, and 8 show portions of an engine accessory mounting bracket that form no part of the claimed design.

The broken lines in FIG. 8 showing an engine are for the purpose of showing environmental structure, and form no part of the claimed design.

1 Claim, 3 Drawing Sheets
